US00D777214S

(12) **United States Design Patent** (10) **Patent No.:** **US D777,214 S**
Moritaka et al. (45) **Date of Patent:** **** Jan. 24, 2017**

(54) **TRACTOR**

(71) Applicant: **MITSUBISHI AGRICULTURAL MACHINERY CO., LTD.**, Shimane-Prefecture (JP)

(72) Inventors: **Yoshiyuki Moritaka**, Shimane-Prefecture (JP); **Yukihiro Komatsu**, Shimane-Prefecture (JP); **Hiromu Kadowaki**, Shimane-Prefecture (JP); **Koji Nakashima**, Shimane-Prefecture (JP); **Satoshi Tamura**, Shimane-Prefecture (JP); **Yasuhiro Kodama**, Shimane-Prefecture (JP); **Keiichi Baba**, Shimane-Prefecture (JP); **Toshinobu Watanabe**, Shimane-Prefecture (JP); **Kenshiro Yakushiji**, Shimane-Prefecture (JP); **Hirotaka Yato**, Shimane-Prefecture (JP); **Akira Kurisu**, Shimane-Prefecture (JP)

(73) Assignee: **Mitsubishi Mahindra Agricultural Machinery Co., Ltd.**, Shimane Prefecture (JP)

(**) Term: **15 Years**

(21) Appl. No.: **29/534,161**

(22) Filed: **Jul. 27, 2015**

(30) **Foreign Application Priority Data**
